[57] **CLAIM**

The ornamental design for combined high density polyethylene bottle and cap, as shown and described.

DESCRIPTION

FIG. 1 is a front elevation of a combined high density polyethylene bottle and cap showing our new design, the rear elevation is a mirror image thereto;

FIG. 2 is a right side elevation of FIG. 1, the left side elevation is the same in appearance except that it lacks the handle;

FIG. 3 is a top plan view;

FIG. 4 is a bottom plan view;

FIG. 5 is a side view of the combined high density polyethylene bottle and cap in FIG. 1 rotated 45°;

FIG. 6 is an enlarged fragmentary view of the handle portion.
